[57] CLAIM

The ornamental design for a dialyzer cartridge, substantially as shown and described.

DESCRIPTION

FIG. 1 is a perspective view of a dialyzer cartridge particularly showing the top and right side thereof of my new design;

FIG. 2 is a bottom plan view, the top plan view is a mirror image of the bottom plan view;

FIG. 3 is a right end view, the left end view is a mirror image of the right end view; and

FIG. 4 is a right side elevational view, the left side elevational view is a mirror image of the right side elevational view.
